(57) **CLAIM**

The ornamental design for a cup with lid, as shown.

DESCRIPTION

FIG. 1 is a front elevational view of a cup with lid, showing my design;

FIG. 2 is a left side elevational view thereof;

FIG. 3 is a right side elevational view thereof;

FIG. 4 is a rear elevational view thereof;

FIG. 5 is a bottom plan view thereof; and,

FIG. 6 is a top plan view thereof.

The broken lines are for illustrative purposes only and form no part of the claimed design.
